(57) CLAIM

The ornamental design for a burp cloth stand and display, as shown and described.

DESCRIPTION

FIG. 1 is a top, front, and right side perspective view of a burp cloth stand and display showing my new design, the broken-line disclosure being for illustrative purposes only and forming no part of the claimed design;

FIG. 2 is a reduced front elevational view thereof;

FIG. 3 is a reduced rear elevational view thereof;

FIG. 4 is a reduced top plan view thereof;

FIG. 5 is a reduced bottom plan view thereof;

FIG. 6 is a reduced right side elevational view thereof; and,

FIG. 7 is a reduced left side elevational view thereof.
